DESIGN FOR A CARRIER

Samuel Locke Breaux, Jr., Oakland, Calif.

Application March 5, 1934, Serial No. 50,948

Term of patent 3½ years

To all whom it may concern:

Be it known that I, SAMUEL LOCKE BREAUX, JR., a citizen of the United States, residing at Oakland, in the county of Alameda and State of California, have invented a new, original, and ornamental Design for a Carrier, of which the following is a specification, reference being had to the accompanying drawing, forming part thereof.

Figure 1 is a side view of a carrier embodying my design.

Figure 2 is a rear view thereof.

Figure 3 is a plan view of the carrier body.

I claim:

The ornamental design for a carrier, as shown.

SAMUEL LOCKE BREAUX, JR.
